UNITED STATES PATENT OFFICE.

SAMUEL WEAVER, OF TROY, NEW YORK, ASSIGNOR OF ONE-HALF TO R. A. MAEDER, OF TROY, NEW YORK.

COAL-OIL BURNER.

1,322,982.

Specification of Letters Patent. Patented Nov. 25, 1919.

Application filed April 8, 1919. Serial No. 288,561.

To all whom it may concern:

Be it known that I, SAMUEL WEAVER, a citizen of the United States, residing at Troy, in the county of Rensselaer and State of New York, have invented a new and useful Coal-Oil Burner, of which the following is a specification.

The device forming the subject matter of this application is an oil burner of that general type wherein a U-shaped conduit is assembled with a box-like casing, and the invention aims to improve the construction of the nozzle and to provide novel means for holding both the nozzle and the conduit on the casing.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described, and claimed, it being understood that, within the scope of what is claimed, changes in the precise embodiment of the invention shown can be made without departing from the spirit of the invention.

In the accompanying drawings:

Figure 1 shows in side elevation, a device constructed in accordance with the invention, parts being broken away; Fig. 2 is a section on the line 2—2 of Fig. 1; and Fig. 3 is a section on the line 3—3 of Fig. 2.

In carrying out the invention there is provided a box-like casing 1 including a body 2 and a top 3. The numeral 4 marks a U-shaped conduit comprising an upper arm 5 and a lower arm 6. The arm 5 has a depending end 7 extended through the top 3 and attached thereto by means of a nut 8. A flame spreader 9 of any desired construction is mounted on the arm 5.

The invention includes a nozzle 10 in the form of a block having a side opening 11 extended but part way through the block. An upwardly extended fuel port 12 is formed in the nozzle 10 and communicates at its lower end with the opening 11. Angular air ports 14 are fashioned in the nozzle or block 10, the upper ends of the air ports communicating with the fuel port 12 near to the upper end thereof, the air ports being

extended downwardly through the lower end of the nozzle 10 and terminating at their lower ends in enlarged recesses 15 whereinto the upper ends of pipes 16 are threaded, the pipes passing through the top 3. Nuts 17 are threaded on the pipes 16 and engage the under surface of the top 3. The pipes 16 may be of any desired length.

The operation of a burner of the type under consideration is clearly understood, but it may be stated that the fuel, having been turned into gas in the arm 5, traverses the lower arm 6 and enters the opening 11 in the nozzle, the fuel passing upwardly through the fuel port 12, air passing upwardly through the pipes 16 and the ports 14 and being delivered into the fuel before the fuel leaves the port 12. The construction of the device is such that an adequate mixture of air and fuel will be provided, a blue flame of intense heat resulting. The pipes 16 exercise a double function, in that they constitute a part of the air supplying means, and constitute also, together with the nuts 17, a means for attaching the block or nozzle 10, and consequently the conduit 4, to the top 3 of the casing 1.

Having thus described the invention, what is claimed is:

1. In a device of the class described, a casing comprising a top; a nozzle on the top, the nozzle having a side opening, a fuel port extended upwardly from the opening, and an air port communicating with the fuel port above the side opening; means for securing the nozzle to the top, said means constituting a continuation of the air port; and a U-shaped conduit including upper and lower arms, the upper arm being disposed above the nozzle, and the lower arm being terminally mounted in the side opening of the nozzle.

2. In a device of the class described, a casing comprising a top; a nozzle on the top, the nozzle having a side opening, a fuel port extended upwardly from the opening, and an air port communicating with the fuel port above the side opening; a pipe passing through the top and threaded into the nozzle at the lower end of the air port; a nut on the pipe and coacting with the under surface of the top; and a U-shaped conduit including upper and lower arms, the upper arm being disposed above the noz-

zle and the lower arm being terminally mounted in the side opening of the nozzle.

3. In a device of the class described, a casing comprising a top; a nozzle on the top, the nozzle having a side opening, a fuel port extended upwardly from the opening, and angular air ports located on opposite sides of the side opening, the ports communicating at their upper ends with the fuel port and opening through the lower end of the nozzle; means for supplying air to the air ports through the top; and a U-shaped

conduit including upper and lower arms, the upper arm being located above the nozzle, and the lower arm being terminally mounted in the side opening of the nozzle. 15

In testimony that I claim the foregoing as my own, I have hereto affixed my signature in the presence of two witnesses.

SAMUEL WEAVER.

Witnesses:

LEWIS T. HUNT,
FREDERICK C. RICE.

It is hereby certified that Letters Patent No. 1,322,982, granted November 25, 1919, upon the application of Samuel Weaver, of Troy, New York, for an improvement in "Coal-Oil Burners," were erroneously issued to the inventor and R. A. Meader as assignee of one-half interest in said invention, whereas said Meader should have appeared as owner of one-twentieth interest only, as shown by the record of assignments in this office; and that the said Letters Patent should be read with this correction therein that the same may conform to the record of the case in the Patent Office.

Signed and sealed this 30th day of December, A. D., 1919.
